(57) **CLAIM**

The ornamental design for a shelving unit, as shown and described.

DESCRIPTION

FIG. 1 is a front view of a first embodiment of a shelving unit;

FIG. 2 is a back view of a first embodiment of a shelving unit;

FIG. 3 is a left view of a first embodiment of a shelving unit;
FIG. 4 is a right view of a first embodiment of a shelving unit;

FIG. 5 is a top view of a first embodiment of a shelving unit;
FIG. 6 is a bottom view of a first embodiment of a shelving unit;

FIG. 7 is a perspective view of a first embodiment of a shelving unit;

FIG. 8 is a front view of a second embodiment of a shelving unit;

FIG. 9 is a back view of a second embodiment of a shelving unit;

FIG. 10 is a left view of a second embodiment of a shelving unit;

FIG. 11 is a right view of a second embodiment of a shelving unit;

FIG. 12 is a top view of a second embodiment of a shelving unit;

FIG. 13 is a bottom view of a second embodiment of a shelving unit;

FIG. 14 is a perspective view of a second embodiment of a shelving unit;

FIG. 15 is a front view of a third embodiment of a shelving unit;

FIG. 16 is a back view of a third embodiment of a shelving unit;

FIG. 17 is a left view of a third embodiment of a shelving unit;

(Continued)

FIG. 18 is a right view of a third embodiment of a shelving unit;
 FIG. 19 is a top view of a third embodiment of a shelving unit;
 FIG. 20 is a bottom view of a third embodiment of a shelving unit;
 FIG. 21 is a perspective view of a third embodiment of a shelving unit;
 FIG. 22 is a front view of a fourth embodiment of a shelving unit;
 FIG. 23 is a back view of a fourth embodiment of a shelving unit;
 FIG. 24 is a left view of a fourth embodiment of a shelving unit;
 FIG. 25 is a right view of a fourth embodiment of a shelving unit;
 FIG. 26 is a top view of a fourth embodiment of a shelving unit;
 FIG. 27 is a bottom view of a fourth embodiment of a shelving unit; and,
 FIG. 28 is a perspective view of a fourth embodiment of a shelving unit.

The dash type broken lines in the Figures are for the purpose of illustrating portions of the shelving unit that form no part of the claimed design.
